UNITED STATES PATENT OFFICE

SADAYOSHI NAKAHARA, OF NEW YORK, N. Y.

DESK SET FOUNTAIN PEN SLEEVE

Application filed September 30, 1931. Serial No. 565,965.

This improvement relates to a fountain pen sleeve for desk sets, which in the present instance is provided with readily adjustable means for varying the effective internal diameter (within the socket) in order that fountain pens with stems of different diameters may be inserted and properly retained firmly in position in the sleeve.

It is also desirable to be able to insert and remove the pen of the desk set without getting ink on the stem thereof and yet have it held closely and firmly in axial position in the sleeve socket. Accordingly, one object of this improvement is to provide a rotary mouth piece for the sleeve which may be readily rotated by the fingers to enlarge or reduce the diameter of the stem supporting part of the socket and to provide means to clamp the stem of the pen firmly after the latter is inserted in the socket. It is important that the pen should be held firmly for the sleeve is supported by a ball and socket joint and may be moved to any angular position between vertical and horizontal.

A further object is to reduce the contact surface of the socket members engaging the stem of the pen substantially to points in order to minimize the chances of getting ink on the stem when the pen is inserted or removed from the sleeve. For this reason, the clamping members forming the socket of variable diameter in the present instance are constituted as balls on the ends of resilient fingers, but obviously other suitable devices may be employed.

One form of the improved desk set fountain pen sleeve and the mounting therefor is shown in the accompanying drawing, in which Fig. 1 is a side view of the desk set with the sleeve in upright position, the sleeve and part of the mounting being shown in section; Fig. 2 represents an enlarged cross section on the line 2-2 of Fig. 1, of the mouth of the sleeve; Fig. 3 is an enlarged vertical cross sectional view of the rotatable mouth portion of the sleeve; Fig. 4 is an enlarged cross sectional view on the line 4-4 of Fig. 1, showing the internal cams for cooperating with the ball fingers

for adjusting the effective diameter of the socket; Fig. 5 is a similar view to Fig. 4, but showing the balls at the bottom of the respective cams and Fig. 6 shows an enlarged perspective view of the ring and integral resilient ball fingers.

Referring to the drawing, it will be seen that the improved desk set fountain pen sleeve is mounted on a base A by a ball and socket joint; the lower end of the sleeve member B being provided with a ball C, secured to the lower end of the sleeve by a screw threaded stem D extending from the ball as shown in Fig. 1. The ball C is mounted and resiliently held in a socket member E, which, as usual, is cut away at the upper end so that the sleeve may be adjusted in any angular position, a notch being provided at F to permit positioning the sleeve horizontally. The ball socket member E is bored out at G and provided with a sliding cup member H, engaging the lower side of the ball C and held in engagement therewith by a spring K which also holds the ball C closely in its socket. The spring K is preferably held in place by a flat headed screw L, which in the present instance, also serves to clamp the ball socket member E to the base A as will be seen in Fig. 1.

The sleeve member B is provided with a central bore or socket M adapted to receive the nib N of the pen which, as shown in Fig. 1, extends downward into the socket M from the stem O of the fountain pen. The sleeve member B, above the socket M, is taperingly counterbored at P and mounted in this counterbore are a plurality of resilient stem supporting centering and gripping fingers Q which, in the present instance, are formed integral with a ring R fitting closely in the bottom of the tapering socket P and secured therein by any suitable means, such as the pin S. The upper ends of the resilient fingers Q are in the present instance, provided with terminal balls T adapted to engage the stem O of the pen and center it relative to the lower or nib socket M. As previously explained the ball fingers are preferably resilient and arranged to be brought to engagement with the stem O of

the pen to center and hold the latter firmly in the sleeve. The resilient ball fingers and the integral ring are more particularly shown in Fig. 6.

In order to adjust the effective diameter of the grip for the stem by adjusting the balls T radially of the sleeve, the upper end of the sleeve is provided with an annular rotatable mouth piece U, mounted for rotation in a straight bored portion at the upper end of the tapering counterbored socket P. The mouth piece U is, in the form illustrated, provided with a depending skirt or cylindrical flange V, having a plurality of inwardly extending cam surfaces W, as will be more particularly seen in Figs. 4 and 5, arranged to cooperate with the balls T. These internal cams extend from a low concave portion at X, lying close to the outer peripheral surface of the flange V of the mouth piece U, and define the outer limit of movement of the balls T and the greatest effective internal diameter or extent of opening for inserting the stem of the pen.

The upper end of the sleeve member B is preferably provided with an internal groove Y, adapted to register with a corresponding annular groove Y' in the outer surface of the cylindrical flange or skirt V of the mouth piece U and a wire spring ring Z is inserted in the grooves Y, Y' in the usual way, to hold the mouth piece U for rotation in the end of the sleeve member B and axially thereof.

In Fig. 4 the cams on the mouth piece are shown with the balls about in the middle of the rise. By rotating the mouth piece U from the position shown in Fig. 4 to the position shown in Fig. 5, the cam surfaces W are moved so that the resiliency of the fingers carry the balls T radially outward to the concave portions X and the effective diameter of the socket is enlarged to the limit as indicated by the dotted circle in Fig. 5. By rotating the mouth piece U in the opposite direction or back to the position shown on Fig. 4, the effective diameter of the socket is reduced, as indicated by the dotted circle in Fig. 4.

From the above, it will be seen that fountain pens of different sizes, or the stems may be of different sizes, may be inserted and used in connection with the desk set sleeve by adjusting the gripping balls T; which may be done by rotating the mouth piece U until the balls engage the stem O of the pen. This arrangement for a variable socket or gripping sleeve for the pen also permits a more ready removal or insertion of the pen, for by rotating the mouth piece U in one direction the effective diameter of the stem socket can be enlarged before inserting the pen and afterwards the stem of the pen can be securely gripped by rotating the mouth piece in the opposite direction. It will be

understood that by means of the gripping balls, the stem of the pen will be engaged substantially by points so that if they should become stained with ink, the point contact of the balls with the stem of the pen will prevent the latter from being covered with ink, which might stain the fingers.

It will be understood that while the preferred form of the improvement has been shown, various modifications in the specific details of construction and arrangement of the essential elements may be made without departing from the spirit and scope of the invention.

I claim:

1. A desk set fountain pen sleeve comprising a socket for the nib of the pen, a counterbored socket portion in the sleeve above said nib socket, a plurality of spring fingers mounted within said counterbored socket portion, said spring fingers being provided at their upper ends with balls for point engagement with the stem of the pen, a rotatable mouth piece mounted at the upper end of the sleeve and provided with a cylindrical skirt portion extending into said counterbored socket portion and internal circumferential cams on said skirt portion cooperating with the ball ends of said spring fingers for varying the radial position of the balls by rotation of said mouth piece.

2. The desk set fountain pen sleeve as in claim 1, wherein said spring fingers with the ball ends are formed integral with a ring adapted to fit into and be secured at the bottom of said counterbored socket portion and said rotatable mouth piece is secured at the upper end of the sleeve with the skirt portion thereof in said counterbored socket portion and held for rotation therein by means cooperating with an annular groove in said skirt portion.
